(57) **CLAIM**

The ornamental design for a jewelry clasp, as shown and described.

DESCRIPTION

FIG. 1 is a front perspective view of a jewelry clasp showing my new design;

FIG. 2 is a front elevation view thereof;

FIG. 3 is a rear elevation view thereof;

FIG. 4 is a top view thereof; and,

FIG. 5 is a perspective view thereof, the bracelet and charm shown in broken lines are for environmental purposes only and form no part of the design.
